Inventor:

Edwin H. Bell

By *Major C. Brown* his Atty.

UNITED STATES PATENT OFFICE.

EDWIN H. BELL, OF CHICAGO, ILLINOIS.

TIE-PLATE.

1,318,334.

Specification of Letters Patent.

Patented Oct. 7, 1919.

Application filed May 17, 1919. Serial No. 297,860.

To all whom it may concern:

Be it known that I, EDWIN H. BELL, a citizen of the United States, and a resident of Chicago, in the county of Cook and State of Illinois, have invented certain new and useful Improvements in Tie-Plates; and I do hereby declare that the following is a full, clear, and exact description thereof, reference being had to the accompanying drawings, and to the numerals of reference marked thereon, which form a part of this specification.

This invention relates to an improvement in tie plates of that type having on the top a rail abutting shoulder and a rail bearing surface, and having on the bottom two flat tie engaging surfaces extending lengthwise of the grain of the tie and a plurality of projections extending at an angle to said tie bearing surfaces and intermediate thereof.

One of the difficulties with a tie plate is to so distribute the metal that the plate shall have the necessary thickness where most needed to resist wear, strain and buckling, and at the same time be relatively thin at other places to reduce the weight of the plate as a whole, and to overcome this difficulty is one of the objects of my invention.

Another object of the invention is to produce a tie plate having the maximum of rigidity and of efficiency in the performance of its intended functions consistent with lightness in weight.

When a rail is placed on the top surface of a tie plate, the spikes driven through the two inside spike holes of the plate are so placed that the outermost rail base flange will not only be parallel with, but will also rest closely against the rail abutting shoulder flange on the top of the tie plate. The spike holes on the inner part of the tie plate are, therefore, usually made somewhat larger than the cross sectional area of the spike, to permit of this rail and tie plate adjustment.

In actual use in track, however, it is found that the said relative positions of the rail and the plate become shifted so that the rail edge will not be parallel with or abut against the shoulder flange throughout its whole length, the spike holes permitting this relative disarrangement of the plate and the rail. To overcome this tendency and to prevent the plate from shifting its position on

the tie and therefore its relative position with respect to the rail, is another object of 55 the present invention.

Another object is to produce a plate having abutments or shoulders on its under side, so disposed as to resist the tendency of the plate to creep or move on the tie transversely of its length and parallel with the direction of the rail.

Another object of the invention is to so distribute the metal, that the plate from which the metal has been removed to lighten 65 the plate may, in use, be concealed from view and in fact, also be protected from the destructive agencies of wind and weather, whereby no water, sand or grit may accumulate between the plate and its tie. 70

Another object of the invention is to produce a commercial tie plate, not only having the advantageous features above referred to, but which may be produced by a "rolling" operation whereby the cost of production may be reduced to a practical and commercial proposition. 75

These and other objects of my invention will be manifest as I proceed herein to describe my improved tie plate. 80

In the drawings:

Figure 1 is a perspective view of a tie plate embodying one form of my invention.

Fig. 2 is a bottom plan view of said plate.

Fig. 3 is a longitudinal, vertical, sectional 85 view of the said tie plate, taken in the plane indicated by the dotted line 3—3 of Fig. 2.

Fig. 4 is a transverse, vertical, sectional view of the same plate, taken upon the plane at right angles to the section shown in Fig. 90 3, and taken as indicated upon the plane indicated by the dotted line 4—4 of Fig. 3.

Fig. 5 is a perspective view of a modified form of tie plate embodying my invention.

Fig. 6 is a bottom plan view, of this modified, enlarged.

Fig. 7 is a longitudinal, vertical, sectional view of the same, taken on the line 7—7 of Fig. 6.

Fig. 8 is a sectional view, similar to that 100 of Fig. 7, showing a modification in the form of the bottom of the plate.

Fig. 9 is a perspective view of another modified form of my invention.

Fig. 10 is a bottom plan view of the modified form of plate shown in Fig. 9. 105

Fig. 11 is a longitudinal, vertical, sectional view of the modified form of Fig. 9, taken in the plane indicated by the dotted line 11-11 of Fig. 10.

5 Fig. 12 is a sectional view, similar to that of Fig. 11, showing yet another modification of my invention.

10 Fig. 13 is a bottom plan view of a tie plate embodying my invention, with a modification showing angularly disposed tie penetrating ribs depending from the tie bearing surfaces.

15 Fig. 14 is a bottom plan view showing another form of tie penetrating ribs upon the tie bearing surfaces.

Referring now to that embodiment of my invention illustrated in Figs. 1 to 4, inclusive, of said drawings, A indicates the tie plate as a whole, which, as shown, is 20 oblong in plan, as usual. The plate is shown as having a flat bearing face T on its top side, which is adapted for engagement with and is of substantially the width of the bottom side of the rail base. At one end 25 of the bearing face T is provided the usual transversely extending, rail abutting flange or shoulder 1. The top side of the plate at its end opposite the rail abutting flange or shoulder 1 is preferably inclined or 30 tapered downwardly toward the end of the plate as shown at 2. The raised up metal constituting the rail abutting shoulder is rounded off at 3; said rounded part then merges in a fillet 4 into the top surface 5 35 of the outer end of the tie plate.

On the bottom surface of the tie plate are provided tie engaging flanges or ribs 6, 6, preferably two, as shown. Said ribs thus extend parallel to the longitudinal axis 40 of the plate A and transversely of the rail abutting shoulder 1 on the top face of the tie plate, and they extend from the end 7 to the end 8 of the tie plate. These flanges 6, 6, are preferably located inside of and 45 parallel to the two side margins 9, 9, thus leaving flat surfaces 10, 10, one on the outside of each flange 6. A similar, though relatively narrow, surface 11 is formed on the inside of each flange 6.

50 In that part of the bottom surface of the tie plate between the two inside surfaces 11, 11, there is formed a plurality of parallel, arcuate undulations, grooves or depressions 12, 12, which extend transversely of 55 the tie plate (that is to say, in this instance, at right angles to the tie engaging flanges 6, 6), and which undulations or grooves 12 are comparatively flat or shallow. The arcuate surfaces of the several grooves intersect in a plurality of parallel lines in the plane of the bottom of the tie plate, thus 60 presenting a plurality of parallel ribs 13, which also extend transversely of the length of the plate, between the inner edges of the 65 surfaces 11, 11, and parallel to the said

undulations or grooves 12. Said ribs 13 thus run across or transversely of the grain of the wood of the tie, when the tie plate is in use, and parallel with the rail abutting shoulder 1, while the flanges 6 run with the 70 grain of the wood.

The bottom surface 10 and the surface 11 of the plate, on both sides of the flanges 6, are flat, and are adapted to rest upon the top surface of the tie.

75

The undulations or grooves 12 below the rail engaging surface of the tie plate, diminish the weight of the plate without materially destroying its strength. It will be noticed particularly, that said undulations or grooves are arranged in a series which extend through the entire length of the plate from the end 7 to the end 8. The ribs 13 extend only between the inner flat surfaces 11, 11, as stated, and consequently 80 the lines of resisting force in said ribs 13 as well as the lines of resistance in said series of flat arched grooves 12, cross at right angles to the lines of resistance of the flanges 6, 6. Thus, the tendency of the plate A to buckle 85 and bend under strain is reduced to a negligible quantity.

The bottom of the tie plate will naturally, under the pressure and pounding of the rail, become slightly depressed into the surface 95 of the tie, and this tends to prevent the shifting of the plate lengthwise of the tie. Since the flanges 6 run in the direction of the length of the plate, that is, parallel to the tie, said flanges being parallel to the 100 fibers of the wood of the tie, will embed themselves between said fibers and will act to prevent the plate from creeping in the direction of the rail, without damaging or distorting the fibers of the wood.

105

The plate is held to the tie by spikes, in a familiar manner, which spikes also tend to prevent the plate from shifting on the tie. The ends 14 of the flanges 6, when the latter are embedded in the tie, act as abutting 110 shoulders to prevent the outward shifting tendency of the plate in use. The points of the ribs 13 normally will rest upon the top surface of the tie and as the use of the plate in track continues and the bottom bearing surfaces 10, 11, are slightly pressed into the surface of the tie, these ribs 13 will 115 similarly enter the tie.

It will be noted that the undulations on the bottom of the plate and above the top 120 of the tie afford no spaces or cavities for the accumulation of water or other deleterious substances, such as sand and grit, inasmuch as each undulation is defined at its side by the transversely extending ribs 13, 125 and at its ends by the tie penetrating flanges 6.

Suitable spike holes are shown, one 130 through the rail abutting shoulder end of the plate and two, 16, 16, through the other

end of the plate. The position of the rail base on the plate is indicated in dotted lines at 17, and of the spikes, by dotted lines at 18. The plate having a flat top bearing 5 face for engagement with the rail base, without grooves or depressions, it is apparent that water will not collect and stand between the rail base and the plate so as to rust and thus gradually destroy and disintegrate the 10 top of the plate. The tie plate thus described is manifestly one that is easy to manufacture in that it is capable of being readily rolled from a billet.

Referring now to the modified form of 15 my invention illustrated in Figs. 5, 6 and 7, it will be noticed that the top rail bearing surface T is not flat throughout its entire width but may be divided into a plurality of surfaces. In this case, three of such surfaces 20 are illustrated, by means of the transversely arranged grooves or depressions 19 extending from side margin to side margin of the plate, and parallel with the rail abutting shoulder. From the bottom of the 25 plate, the depending, tie penetrating ribs or flanges 6, 6 of the previous form, have been omitted, so that the two tie bearing surfaces 10 and 11 of said first form, are merged into a single tie bearing surface 20, 20, one at 30 each side of the plate, and extending from end to end thereof, with the arcuate undulations or grooves 12, 12, intermediate thereof.

In Fig. 8, I have illustrated a modification 35 of the form of parallel, arcuate undulations or grooves 12, 12, showing the surfaces of said grooves intersecting in a plurality of lines in a plane just below the bottom of the tie plate, thus presenting a plurality of relatively short, parallel, tie penetrating 40 ribs or points of metal, 21, 21. Where the longitudinally arranged flanges or ribs 6, 6, are omitted, as in the form shown in Figs. 5 to 7, inclusive, I prefer to so extend the 45 intersecting surfaces of the arcuate undulations or depressions 12, 12, as to form these projecting points or ribs 21, 21, which when the plate is placed upon the tie, enter and engage the tie and prevent shifting of the plate thereon.

50 Referring now to the modification shown in Figs. 9, 10 and 11, it will be noticed that the top of the plate instead of having a flat rail bearing surface, is provided with a plurality of ribs 22 extending from the rail abutting shoulder lengthwise of the plate and preferably, as shown, thicker at the shoulder than at the opposite end. These 55 ribs 22 are preferably somewhat rounded on their upper or rail bearing surfaces, as shown at 23. The bottom of the plate shown in Figs. 9, 10 and 11, is substantially the same as the plate illustrated in Figs. 1, 2 and 3, previously described, with the exception that the transverse undulations or

grooves 12, 12, and their intervening ribs 66 13, 13, while parallel to each other, extend lengthwise of the plate at a different angle to the side margin of the surfaces 20; that is, diagonally instead of at right angles.

In the form shown in Fig. 12, the top 70 surface of the plate is provided with grooves or depressions 19, and the ribs or flanges 6, 6, are omitted.

In the modification shown in Fig. 13, the longitudinally extending ribs or flanges, indicated at 24, as depending from the tie bearing surface 20 of the plate, are shown as extending angularly to the side margin of the surface 20 and from one end of the plate to the other; one rib being shown on 80 each tie bearing surface.

In the modification shown in Fig. 14, the tie bearing surface 20 is provided with a plurality of angularly disposed, tie penetrating 85 ribs 25, 25.

While I have illustrated a tie plate in Figs. 1 to 4, inclusive, with the arcuate undulations 12 and the ribs 13 extending at right angles to the flanges 6, 6, as my preferred form, it is manifest that not only the 90 modifications shown but other modifications may be made without departing from the principle of my invention, the essential features of which comprise two parallel, tie bearing surfaces on the bottom of the plate, 95 one at each side thereof, and an intermediate section of parallelly arranged, arcuate grooves or depressions intermediate of and extending to said tie bearing surfaces, and at an angle thereto. I have described the 100 set of parallel undulations or grooves 12, 12, as being arcuate undulations, but it is manifest that the precise geometrical form of the surfaces 12, 12, illustrated, may not be followed in all cases, as it is clear that the 105 essential feature of this part of my invention consists in having a series of depressions in the bottom of the plate, extending between the bearing surfaces 20, 20, so joined as to form the intervening ribs 13. 110

I claim as my invention:

1. A tie plate having on its top a rail bearing surface and a transversely arranged rail abutting shoulder, and having on its bottom two parallel tie bearing surfaces extending in the direction of the length of the tie, and intermediate said bearing surfaces a plurality of parallel, flattened, arcuate undulations or grooves extending from one tie bearing surface to the other, the surfaces 115 of said undulations or grooves intersecting in lines to form dividing ribs, said undulations or grooves being of such number as to extend throughout the length of the plate.

2. A tie plate having on its top a rail bearing surface and a transversely arranged rail abutting shoulder, and having on its bottom two parallel tie bearing surfaces ex- 125

- 1 tending in the direction of the length of the tie, and intermediate said bearing surfaces a plurality of parallel, flattened, arcuate undulations or grooves extending from one tie bearing surface to the other and at an angle to the inner margin of said bearing surfaces, the surfaces of said undulations or grooves intersecting in lines to form dividing ribs, said undulations or grooves being of such number as to extend throughout the length of the plate.
3. A tie plate having on its top a rail bearing surface and a transversely arranged rail abutting shoulder, and having on its bottom two parallel tie bearing surfaces extending in the direction of the length of the tie, and intermediate said bearing surfaces a plurality of parallel, flattened, arcuate undulations or grooves extending from one tie bearing surface to the other, the surfaces of said undulations or grooves intersecting in lines to form dividing ribs terminating in the plane of said tie bearing surfaces, said undulations or grooves being of such number as to extend throughout the length of the plate.
4. A tie plate having on its top a rail bearing surface and a transversely arranged rail abutting shoulder, and having on its bottom two parallel tie bearing surfaces extending in the direction of the length of the tie, and intermediate said bearing surfaces a plurality of parallel, flattened, arcuate undulations or grooves extending from one tie bearing surface to the other and at an angle to the inner margin of said bearing surfaces, the surfaces of said undulations or grooves intersecting in lines to form dividing ribs terminating in the plane of said tie bearing surfaces, said undulations or grooves being of such number as to extend throughout the length of the plate.
5. A tie plate having on its top a rail bearing surface and a transversely arranged rail abutting shoulder, and having on its bottom two parallel tie bearing surfaces extending in the direction of the length of the tie, intermediate said bearing surfaces a plurality of parallel, flattened, arcuate undulations or grooves extending from one tie bearing surface to the other, the surfaces of said undulations or grooves intersecting in lines to form dividing ribs, said undulations or grooves being of such number as to extend throughout the length of the plate, and a downwardly projecting, tie penetrating rib on each tie bearing surface extending generally in the direction of the length of the tie.
6. A tie plate having on its top a rail bearing surface and a transversely arranged rail abutting shoulder, and having on its bottom two parallel tie bearing surfaces extending in the direction of the length of the tie, and intermediate said bearing surfaces a plurality of parallel, flattened, arcuate undulations or grooves extending from one tie bearing surface to the other, the surfaces of said undulations or grooves intersecting in lines to form dividing ribs, said undulations or grooves being of such number as to extend throughout the length of the tie.
7. A tie plate having on its top a rail bearing surface and a transversely arranged rail abutting shoulder, and having on its bottom two parallel tie bearing surfaces extending in the direction of the length of the tie, intermediate said bearing surfaces a plurality of parallel, flattened, arcuate undulations or grooves extending from one tie bearing surface to the other, the surfaces of said undulations or grooves intersecting in lines to form dividing ribs terminating in the plane of said tie bearing surfaces, said undulations or grooves being of such number as to extend throughout the length of the plate, and a downwardly projecting, tie penetrating rib on each tie bearing surface extending generally in the direction of the length of the tie.
8. A tie plate having on its top a rail bearing surface and a transversely arranged rail abutting shoulder, and having on its bottom two parallel tie bearing surfaces extending in the direction of the length of the tie, intermediate said bearing surfaces a plurality of parallel, flattened, arcuate undulations or grooves extending from one tie bearing surface to the other and at an angle to the inner margin of said bearing surfaces, the surfaces of said undulations or grooves intersecting in lines to form dividing ribs terminating in the plane of said tie bearing surfaces, said undulations or grooves being of such number as to extend throughout the length of the plate, and a downwardly projecting, tie penetrating rib on each tie bearing surface, extending generally in the direction of the length of the tie.
9. A tie plate having upon its top a rail bearing surface, a transversely arranged rail abutting shoulder, and a groove or grooves in the rail bearing surface parallel to the rail abutting shoulder, and having on its bottom two parallel tie bearing surfaces extending in the direction of the length of the tie, and intermediate said bearing surfaces a plurality of parallel, flattened, arcuate undulations or grooves extending from one tie bearing surface to the other, the surfaces of said undulations or grooves intersecting in lines to form dividing ribs, said undulations or grooves being of such number as to extend throughout the length of the tie.

to extend throughout the length of the plate.

10. A tie plate having upon its top a rail bearing surface, a transversely arranged rail abutting shoulder, and a groove or grooves in the rail bearing surface parallel to the rail abutting shoulder, and having on its bottom two parallel tie bearing surfaces extending in the direction of the length of the tie, and intermediate said bearing surfaces a plurality of parallel, flattened, arcuate undulations or grooves extending from one tie bearing surface to the other and at an angle to the inner margin of said bearing surfaces,
15. the surfaces of said undulations or grooves intersecting in lines to form dividing ribs, said undulations or grooves being of such number as to extend throughout the length of the plate.
20. 11. A tie plate having upon its top a rail bearing surface, a transversely arranged rail abutting shoulder, and a groove or grooves in the rail bearing surface parallel to the rail abutting shoulder, and having on its bottom two parallel tie bearing surfaces extending in the direction of the length of the tie, and intermediate said bearing surfaces a plurality of parallel, flattened, arcuate undulations or grooves extending from one tie bearing surface to the other, the surfaces of said undulations or grooves intersecting in lines to form dividing ribs terminating in the plane of said tie bearing surfaces, said undulations or grooves being of such number as to extend throughout the length of the plate.
25. 30. 35.

12. A tie plate having upon its top a rail bearing surface, a transversely arranged rail abutting shoulder, and a groove or grooves 40 in the rail bearing surface parallel to the rail abutting shoulder, and having on its bottom two parallel tie bearing surfaces extending in the direction of the length of the tie, and intermediate said bearing surfaces 45 a plurality of parallel, flattened, arcuate undulations or grooves extending from one tie bearing surface to the other and at an angle to the inner margin of said bearing surfaces, the surfaces of said undulations or grooves 50 intersecting in lines to form dividing ribs terminating in the plane of said tie bearing surfaces, said undulations or grooves being of such number as to extend throughout the length of the plate.

55 13. A tie plate having upon its top a rail bearing surface, a transversely arranged rail abutting shoulder, and a groove or grooves in the rail bearing surface parallel to the rail abutting shoulder, and having on its
60 bottom two parallel tie bearing surfaces extending in the direction of the length of the tie, intermediate said bearing surfaces a plurality of parallel, flattened, arcuate undulations or grooves extending from one tie bear-

ing surface to the other, the surfaces of said undulations or grooves intersecting in lines to form dividing ribs, said undulations or grooves being of such number as to extend throughout the length of the plate, and a downwardly projecting, tie penetrating rib 70 on each tie bearing surface, extending generally in the direction of the length of the tie.

any in the direction of the length of the tie.
14. A tie plate having upon its top a rail bearing surface, a transversely arranged rail abutting shoulder, and a groove or grooves 75 in the rail bearing surface parallel to the rail abutting shoulder, and having on its bottom two parallel tie bearing surfaces extending in the direction of the length of the tie, intermediate said bearing surfaces a plurality 80 of parallel, flattened, arcuate undulations or grooves extending from one tie bearing surface to the other and at an angle to the inner margin of said bearing surfaces, the surfaces of said undulations or grooves intersecting in lines to form dividing ribs, said undulations or grooves being of such number as to extend throughout the length of the plate, and a downwardly projecting, tie penetrating rib on each tie bearing surface 85 90 extending generally in the direction of the length of the tie.

15. A tie plate having upon its top a rail bearing surface, a transversely arranged rail abutting shoulder, and a groove or grooves 95 in the rail bearing surface parallel to the rail abutting shoulder, and having on its bottom two parallel tie bearing surfaces extending in the direction of the length of the tie, intermediate said bearing surfaces a plurality 100 of parallel, flattened, arcuate undulations or grooves extending from one tie bearing surface to the other, the surfaces of said undulations or grooves intersecting in lines to form dividing ribs terminating in the plane 105 of said tie bearing surfaces, said undulations or grooves being of such number as to extend throughout the length of the plate, and a downwardly projecting, tie penetrating rib 110 on each tie bearing surface extending generally in the direction of the length of the tie.

16. A tie plate having upon its top a rail bearing surface, a transversely arranged rail abutting shoulder, and a groove or grooves 115 in the rail bearing surface parallel to the rail abutting shoulder, and having on its bottom two parallel tie bearing surfaces extending in the direction of the length of the tie, intermediate said bearing surfaces a plurality of parallel, flattened, arcuate undulations or grooves extending from one tie bearing surface to the other and at an angle to the inner margin of said bearing surfaces, the surfaces of said undulations or grooves intersecting in lines to form dividing ribs terminating in the plane of said tie bearing surfaces, said undulations or grooves being 120 125

of such number as to extend throughout the length of the plate, and a downwardly projecting, tie penetrating rib on each tie bearing surface, extending generally in the direction of the length of the tie.

In testimony, that I claim the foregoing as my invention I affix my signature in the

presence of two witnesses, this 14th day of May A. D. 1919.

EDWIN H. BELL.
